UNITED STATES PATENT OFFICE.

PATRICK REYNOLDS, OF FARNHAM, AND JOSEPH ALPHONSE RAOUL BEDARD, OF QUEBEC, CANADA; SAID BEDARD ASSIGNOR TO JOSEPH WILLIAM HARRIS, OF MONTREAL, CANADA.

PEAT-DRYING APPARATUS.

No. 799,939.

Specification of Letters Patent.

Patented Sept. 19, 1905.

Application filed June 2, 1904. Renewed April 21, 1905. Serial No. 256,801.

To all whom it may concern:

Be it known that we, PATRICK REYNOLDS, of Farnham, county of Missisquoi, and JOSEPH ALPHONSE RAOUL BEDARD, of Quebec, county of Quebec, in the Province of Quebec, Canada, subjects of the King of Great Britain, have invented certain new and useful Improvements in Peat-Drying Apparatus; and we do hereby declare that the following is a full, clear, and exact description of the invention, such as will enable others skilled in the art to which it appertains to make and use the same.

This invention relates to new and useful improvements in drying apparatus designed especially for use in drying peat incidental to the process of preparing such peat for use as fuel, and comprises certain features of novelty in the construction and operation thereof and in the appurtenant connections therefor by means of which impurities and foreign matter are expelled from the peat, all as hereinafter more fully described, and specifically pointed out in the claims.

The object of the invention is to provide an apparatus of the character indicated by means of which peat may be freed from foreign substances—such as sticks, stones, &c.—when taken from the bog and passed through the apparatus herewith illustrated, so that the peat is partially dried therein and rendered suitable for compression into briquets without the admixture of any foreign substances for the purpose of binding the particles thereof together.

The apparatus and its appurtenant parts are illustrated in the annexed drawings to some extent diagrammatically for convenience of illustration, owing to the fact that a number of elements which are well known in the art are used in connection with the general apparatus, and while we do not claim specifically such well-known elements except as a correlation of result may be produced from their operation in our apparatus we do not specifically disclaim any of the features herewith illustrated or the process herein partially disclosed, as such process will form the subject-matter of a separate application or applications for patents.

Referring to the annexed drawings, wherein similar numerals of reference indicate corresponding parts in all the views, Figure 1 is a side elevational view of our improved ap-

paratus, partly diagrammatically illustrated. Fig. 2 is an approximate end elevation, being taken on the line 22 of Fig. 1. Fig. 3 is a transverse vertical sectional view taken on the line 33 of Fig. 4. Fig. 4 is a longitudinal vertical sectional view of that part of the apparatus disclosed in Fig. 1 within the lines 44 and hereinafter specifically referred to as a "breaker-chamber" and "breaker." Fig. 5 is a transverse sectional view taken on the line 55 of Fig. 6 looking in the direction indicated by the arrow. Fig. 6 is a sectional view taken approximately on the line 66 of Fig. 12, except that the conveyer-blades disclosed in Figs. 6 and 12 are shown in elevation in Fig. 6. Fig. 7 is a transverse sectional view taken on the line 77 of Fig. 6, with the addition of the steam-supply main and lateral feed-pipe being connected to the coils disclosed in Fig. 7. Fig. 8 is a detached detail sectional view taken vertically through the pug-mill on the line 88 of Fig. 9. Fig. 9 is a vertical sectional view taken on the line 99 of Fig. 8. Fig. 10 is an enlarged detail view of one of the conveyer-blades hereinafter referred to. Fig. 11 is a similar view of the opposite side of said blade, and Fig. 12 is a vertical sectional view taken on the line 1212 of Fig. 1.

For convenience of description several of the machine elements are referred to by arbitrary names, and wherever used such names indicate said parts or mechanical equivalents thereof, whether constructed in the same manner or in any other manner, whereby such parts may be capable of performing the required function ascribed to the parts or elements so named. For example, the "breaker" includes means whereby rotatable elements or fingers are applied for the purpose of ejecting from the peat such foreign matter as sticks, stones, &c., which it is desired to eliminate from the finished product. The "conveyer" includes any required number of propeller-blades or their mechanical equivalent adapted to cause the peat to travel in its course through the apparatus. The "apertured wall" or "perforated walls" include either a wall or walls formed of any number of elements, with passages or apertures therethrough or between the same whereby the peat may pass from one side to the other of such wall. "Pug-mill" includes any means adapted to perform

the usual function of such mills, whether of the form shown or any other suitable construction. "Heater" includes a fuel-combustion chamber and appurtenant connections or other known means for raising the temperature, and likewise "superheater" includes a chamber heated directly by the products of combustion or by any other means, such as steam, &c., for accomplishing the purpose, as will be evident from the annexed illustration of our invention, wherein the heater and the superheater are one and the same apparatus.

That the apparatus may be better understood reference will be made to the parts in substantially the order in which the elements referred to become operative for accomplishing the purpose of the machine, as follows:

1 is a conveyer or elevator which may be used for the purpose of elevating the moist peat to the machine or dumping it into the hopper 2, through which it is conducted into the breaker-chamber 3, wherein the shaft 4, provided with the adjusting extension 5, rotates. Upon the shaft 4 are any suitable number of propeller-blades 6, adapted to drive the peat longitudinally of the chamber 3, while breaker-arms 7 are carried by the shaft 4, but which are not caused to rotate therewith. Interposed between the propellers 6 and breaker-arms 7 are fingers 8, which are keyed to the shaft and rotate with it, or said fingers are provided with non-circular seats adapted to rest upon and be engaged by non-circular portions of said shaft, as shown in Fig. 3, whereby as the peat is forced through the breaker-chamber 3 the arms 7 and 8 coöperate to drive sticks and large particles of earth or stones and other matter from the mass of wet peat into the breaker-depositing chamber 9, which extends laterally from the chamber 3, as best shown in Fig. 3 of the drawings.

As will be noted in Fig. 3, the arms 7 are mounted upon the shaft 4, which is non-circular in cross-section. Between the shaft and these arms is a friction-disk 7^a, which rotates with the shaft and by frictional engagement carries the arms 7 in the direction indicated by the arrow in that figure. The free ends of the arms 7 extend into the chamber 9, as shown, and when actuated contact with the shoulder 9^a with sufficient force so that they are thereby returned to the position shown in Fig. 3, from which position they are again elevated during continued rotation of said shaft, thus causing said arms 7 to travel only for that portion of a circle between the lower and upper walls of chamber 9.

The chamber 9 is provided with a door 10, having a suitable locking means 11 of any convenient description for the purpose of securing such door in closed position, and it will be evident that at intervals such door 10 should be opened and the contents of the chamber 9

removed therefrom to prevent an excessive accumulation therein.

Any suitable number of breaker arms and fingers 7 and 8 may be provided within the breaker-chamber according to the capacity of the machine, and the relative proportion thereof may be changed at will, according to the class of material to be operated on and the known foreign matter contained therein.

The breaker-chamber 3 opens into a drying-chamber or conveying-chamber 12, which is shown in elevation in Fig. 1. Extending longitudinally of the drying-chamber 12 is a main steam-supply pipe 13, from which branches 14 extend and communicate with the upper convolution of the coils 15, which comprise what are herein referred to as "aper-tured walls," such apertures consisting of the spaces or openings between the several convolutions of such pipe 15. Supporting the apertured walls in position are angle-irons 16, which, as shown in Fig. 6, are disposed at each side of said walls, so as to better enable them to serve as strainers and resisting means for the peat to be projected therethrough. The lower portion of the chamber 12 is curved, as shown in Fig. 7, and the bottom formed by the curved plate 17 is apertured at convenient intervals for the insertion of a plurality of such apertured walls 15 between the bottom sections produced by such openings. Interposed between the apertured walls are conveyer-blades 18, shown in detail in Figs. 10 and 11 and comprising the hubs 19, having the integral arms 20, to which are bolted or otherwise secured the face-plates 21, while set-screws 22 are projected through the hubs 19 for the purpose of securing such conveyer-blades upon the shaft 4^a, which is an extension of the shaft 4 before referred to and in alinement therewith.

The conveyers 18 will cause the peat driven from the chamber 3 into the heating-chamber 12 to be passed through the perforated walls 15, whereby a separation of the particles of such peat will result, owing to the action of the conveyers, which serve as disintegrating as well as conveying means, and the relatively fine mesh caused by the close proximity of the coils constituting the walls 15. A relatively large number of such walls 15 are provided within the chamber 12, and according to the capacity of the apparatus the number of such walls may be increased or diminished as experience will demonstrate to be most desirable.

In convenient proximity to the heating-chamber 12 is provided a suitable heating apparatus, which for convenience of illustration is shown in the drawings as comprising the combustion-chamber 25, which may be of any suitable character, within and through which project a number of coils of pipe, as follows: Near the feed end of the apparatus

is placed a blower 26, from which extends a pipe 27, which passes into and through the heater, thence rises, as shown in Fig. 1, and communicates with the feed end of the drying-chamber 12, whereby a hot blast is projected into such drying-chamber. At the opposite end of the apparatus a fan 28 is provided, from which extends the conduit 29 through the heater and to the discharge end 10 of the drying-chamber, where such pipe 29 enters the heating-chamber. A steam-supply pipe 30, which leads, preferably, from the exhaust of the engine used to drive the apparatus, passes through the heater, whereby steam therein is superheated and conducted to the supply-main 13, which main is closed by suitable plugs 31 at its ends, as shown in Fig. 1 of the drawings, so that steam therein will be permitted to pass through the branches 15, 14, thence through the coils 15, and exhaust through the branches 32 into the exhaust-main 33, which leads to atmosphere, as indicated by the arrow in Fig. 1.

Leading from the upper portion of the combustion-chamber 25 is a conduit 34, which leads to approximately the middle portion of the heating-chamber 12, whereby the spent products of combustion and heated gases from the combustion-chamber are carried into said heating-chamber, thereby utilizing to the fullest extent possible all of the available heating means for the purpose of drying the peat without carbonizing the same. Connecting with the combustion-chamber intermediate its ends, and preferably between the hot-air conduits 27, 29, and 34, are exhaust-conduits 35, which lead to exhaust-fans 36, whereby the aqueous vapors generated within the heating-chamber 12 are exhausted to atmosphere, and the dry air and gases and the superheated steam in the apertured walls are rendered available to their fullest capacity for the purpose of evaporating moisture from the peat passed through the said heating-chamber. The shaft 4 4^a is rotated by means of the beveled gear 37, meshing with the corresponding beveled gear 38 upon the shaft 39, upon which is placed a pulley 40, driven from the driving-shaft 41, and the said blast-fans and exhaust-fans are likewise driven by suitable belting or other well-known connections from the engine represented diagrammatically in 42. When the peat has been passed the entire length of the heating-chamber 12 by means of the conveyers, such peat passes from the said chamber into a suitable pug-mill 44, in which further disintegration of such peat takes place, after which it is fed by the feed-wheel thereof into the conduit 45. In convenient proximity to the pug-mill 44 is a blast-fan 46, discharging into said conduit 45, by means of which the peat, which is now comparatively dry, is fed through the heating-chamber 25 by means of such blast generated by the fan 46, and after passing through the

heater the peat is discharged from the pipe 45 to any suitable place of deposit, or, if desired, is carried to any suitable briquetting machine (not shown) for the purpose of forming it into briquets for the market.

As will be evident from the foregoing description, the invention comprises a self-contained apparatus wherein each of the elements contributes its quota to the general result of cleaning, disintegrating, and drying the peat in its passage through the apparatus, and by means of the apparatus hereinbefore particularly described we are enabled to take peat which is in a moist condition and conduct it through the machine, and thereby produce an article of commerce wherein all of the caloric value of the peat is retained, yet placing such peat in the best possible condition for forming it into the usual briquets for consumption.

While we have shown in the accompanying drawings the preferred form of our invention, it will be understood that we do not limit ourselves to the precise form shown, for many of the details may be changed in form or position without affecting the operativeness or utility of our invention, and we therefore reserve the right to make all such modifications as are included within the scope of the following claims or of mechanical equivalents to the structures set forth.

43 is a roller-brush coöperating with the serrations 43^a, which serves to disintegrate the peat from the heating-chamber to the pug-mill 44.

Having described our invention, what we claim, and desire to secure by Letters Patent, is—

1. In an apparatus of the character described, a conveyer-chamber, conveyers therein, apertured walls between said conveyers, a heater, a blast-conduit leading through the heater to said conveyer-chamber, and an exhaust from said chamber.

2. In an apparatus of the character described, a conveyer-chamber, a conveyer-shaft, conveyers thereon, apertured walls between said conveyers, a heater, and conduits therefrom to said conveyer-chamber.

3. In an apparatus of the character described, a conveyer-chamber, a conveyer-shaft projected longitudinally thereof, apertured walls intermediate the ends thereof, conveyers between said walls, and means for conducting heat to said chamber.

4. In an apparatus of the character described, a conveyer-chamber, a conveyer-shaft projected longitudinally thereof, apertured walls intermediate the ends of said shaft, conveyers between said walls, means for conducting heat to said walls, and independent heat-conducting means leading to said chamber.

5. In an apparatus of the character described, a chamber, a plurality of apertured

- hollow walls extending transversely thereof, means for conducting heat to the interior of said walls, a conveyer, an exhaust, and independent means for heating said chamber.
- 5 6. In an apparatus of the character described, a chamber, a plurality of apertured hollow walls extending transversely thereof, braces for said walls, means for conducting heat to the interior of said walls, a conveyer, 10 an exhaust, and independent means for heating said chamber.
- 15 7. In an apparatus of the character described, a conveyer-chamber, a plurality of apertured hollow walls extending transversely thereof, a conveyer, a heater, conduits from said heater to the interior of said walls and to the interior of said chamber, a pug-mill and a blast-conduit leading from the discharge thereof.
- 20 8. In an apparatus of the character described, a conveyer-chamber, a plurality of apertured walls extending transversely thereof, a conveyer, a heater, a plurality of blast-conduits leading from said heater to said chamber, and exhausts leading from said chamber.
- 25 9. In an apparatus of the character described, a conveyer-chamber, a plurality of apertured hollow walls extending transversely thereof, a conveyer, a heater, a plurality of blast-conduits leading from said heater to the said walls and to said chamber, and exhausts leading from said chamber.
- 30 10. In an apparatus of the character described, a conveyer-chamber, a plurality of apertured walls extending transversely thereof, a conveyer, a heater, a plurality of blast-conduits leading therefrom to opposite end portions of said chamber, a vapor-conduit 35 leading from said heater to said chamber, and exhausts from said chamber.
- 40 11. In an apparatus of the character described, a conveyer-chamber, a plurality of apertured walls extending transversely thereof, a conveyer, a heater, a plurality of blast-conduits leading therefrom to opposite end portions of said chamber, a vapor-conduit leading from said heater to said chamber, and exhausts from said chamber intermediate 45 said vapor-conduit and said blast-conduits.
- 45 12. In an apparatus of the character described, a conveyer-chamber, conveyers therein, apertured walls between said conveyers, a heater, a blast-conduit leading through the heater to said conveyer-chamber, and an exhaust from said chamber, in combination with a steam-supply conduit leading through said heater and to the said walls.
- 50 13. In an apparatus of the character described, a conveyer-chamber, a conveyer-shaft, conveyers thereon, apertured walls between said conveyers, a heater, and conduits therefrom to said conveyer-chamber, in combination with a steam-supply conduit leading 55 through said heater and to the said walls.
- 55 14. In an apparatus of the character described, a conveyer-chamber, a conveyer-shaft projected longitudinally thereof, apertured walls intermediate the ends thereof, conveyers between said walls, and means for heating said chamber, in combination with a steam-supply conduit leading through said heater and to the said walls.
- 60 15. In an apparatus of the character described, a conveyer-chamber, a conveyer-shaft projected longitudinally thereof, apertured walls intermediate the ends of said shaft, conveyers between said walls, heat-conducting means leading to said walls, and independent heat-conducting means leading to 65 said chamber, in combination with a steam-supply conduit leading through said heater and to the said walls.
- 65 16. In an apparatus of the character described, a conveyer-chamber, a plurality of apertured walls extending transversely thereof, a conveyer, a heater, a plurality of blast-conduits leading from said heater to said chamber, and exhausts leading from said chamber, in combination with a steam-supply conduit leading 70 through said heater and to the said walls.
- 70 17. In an apparatus of the character described, a conveyer-chamber, a plurality of apertured hollow walls extending transversely thereof, a conveyer, a heater, a plurality of blast-conduits leading from said heater to the said walls and to said chamber, and exhausts leading from said chamber, in combination with a steam-supply conduit leading 75 through said heater and to the said walls.
- 75 18. In an apparatus of the character described, a conveyer-chamber, a plurality of apertured walls extending transversely thereof, a conveyer, a heater, a plurality of blast-conduits leading therefrom to opposite end portions of said chamber, a vapor-conduit leading from said heater to said chamber, and exhausts from said chamber, in combination 80 with a steam-supply conduit leading through said heater and to the said walls.
- 80 19. In an apparatus of the character described, a breaker-chamber having a lateral extension, a breaker therein, a conveyer-chamber, conveyers therein, apertured walls between said conveyers, a heater, a blast-conduit leading through the heater to said conveyer-chamber, and an exhaust from said chamber.
- 85 20. In an apparatus of the character described, a breaker-chamber having a lateral extension, a breaker therein, a conveyer-chamber, a conveyer-shaft, conveyers thereon, apertured walls between said conveyers, a heater, and conduits therefrom to said conveyer-chamber.
- 90 21. In an apparatus of the character described, a breaker-chamber having a lateral extension, a breaker therein, a conveyer-chamber, a conveyer-shaft projected longitudinally thereof, apertured walls intermediate the ends 95

thereof, conveyers between said walls, and means for supplying heat to said chamber.

22. In an apparatus of the character described, a breaker-chamber having a lateral extension, a breaker therein, a conveyer-chamber, a conveyer-shaft projected longitudinally thereof, apertured walls intermediate the ends of said shaft, conveyers between said walls, means for conducting heat to said walls, and independent heat-conducting means leading to said chamber.

23. In an apparatus of the character described, a breaker-chamber having a lateral extension, a breaker therein, a conveyer-chamber, a plurality of apertured walls extending transversely thereof, a conveyer, a heater, a plurality of blast-conduits leading from said heater to said chamber, and exhausts leading from said chamber.

24. In an apparatus of the character described, a breaker-chamber having a lateral extension, a breaker therein, a conveyer-chamber, a plurality of apertured hollow walls extending transversely thereof, a conveyer, a heater, a plurality of blast-conduits leading from said heater to the said walls and to said chamber, and exhausts leading from said chamber.

25. In an apparatus of the character described, a breaker-chamber having a lateral extension, a breaker therein, a conveyer-chamber, a plurality of apertured walls extending transversely thereof, a conveyer, a heater, a plurality of blast-conduits leading therefrom to opposite end portions of said chamber, a vapor-conduit leading from said heater to said chamber, and exhausts from said chamber.

26. In an apparatus of the character described, a breaker-chamber having a lateral extension, a breaker therein, a conveyer-chamber, conveyers therein, apertured walls between said conveyers, a heater, a blast-conduit leading through the heater to said conveyer-chamber, and an exhaust from said chamber, in combination with a steam-supply conduit leading through said heater and to the said walls.

27. In an apparatus of the character described, a breaker-chamber having a lateral extension, a breaker therein, a conveyer-chamber, a conveyer-shaft, conveyers thereon, apertured walls between said conveyers, a heater, and conduits therefrom to said conveyer-chamber, in combination with a steam-supply conduit leading through said heater and to the said walls.

28. In an apparatus of the character described, a breaker-chamber having a lateral extension, a breaker therein, a conveyer-chamber, a conveyer-shaft projected longitudinally thereof, apertured walls intermediate the ends thereof, conveyers between said walls, and heat-conducting means leading to said chamber, in combination with a steam-supply con-

duit leading through said heater and to the 65 said walls.

29. In an apparatus of the character described, a breaker-chamber having a lateral extension, a breaker therein, a conveyer-chamber, a conveyer-shaft projected longitudinally 70 thereof, apertured walls intermediate the ends of said shaft, conveyers between said walls, means for conducting heat to said walls, and independent heat-conducting means leading to said chamber, in combination with a steam-supply conduit leading through said heater and to the said walls.

30. In an apparatus of the character described, a breaker-chamber having a lateral extension, a breaker therein, a conveyer-chamber, a plurality of apertured walls extending 80 transversely thereof, a conveyer, a heater, a plurality of blast-conduits leading from said heater to said chamber, and exhausts leading from said chamber, in combination with a 85 steam-supply conduit leading through said heater and to the said walls.

31. In an apparatus of the character described, a breaker-chamber having a lateral extension, a breaker therein, a conveyer-chamber, a plurality of apertured hollow walls extending transversely thereof, a conveyer, a heater, a plurality of blast-conduits leading from said heater to the said walls and to said chamber, and exhausts leading from said chamber, in combination with a steam-supply conduit leading through said heater and to the 95 said walls.

32. In an apparatus of the character described, a breaker-chamber having a lateral extension, a breaker therein, a conveyer-chamber, a plurality of apertured walls extending transversely thereof, a conveyer, a heater, a plurality of blast-conduits leading therefrom to opposite end portions of said chamber, a 100 vapor-conduit leading from said heater to said chamber, and exhausts from said chamber, in combination with a steam-supply conduit leading through said heater and to the 105 said walls.

33. In an apparatus of the character described, a breaker-chamber, a breaker therein comprising a supporting-shaft, a plurality of breaker-arms fixed upon said shaft, conveyer-blades also fixed to said shaft, a plurality of loosely-mounted breaker-arms, and a conveyer-chamber, conveyers therein, apertured walls between said conveyers, a heater, a blast-conduit leading through the heater to said conveyer-chamber, and an exhaust from said chamber.

34. In an apparatus of the character described, a breaker-chamber, a breaker therein comprising a supporting-shaft, a plurality of breaker-arms fixed upon said shaft, conveyer-blades also fixed to said shaft, a plurality of loosely-mounted breaker-arms, and a conveyer-chamber, a conveyer-shaft, conveyers thereon, apertured walls between said con-

veyers, a heater, and conduits therefrom to said conveyer-chamber.

35. In an apparatus of the character described, a breaker-chamber, a breaker therein comprising a supporting-shaft, a plurality of breaker-arms fixed upon said shaft, conveyer-blades also fixed to said shaft, a plurality of loosely-mounted breaker-arms, and a conveyer-chamber, a conveyer-shaft projected longitudinally thereof, apertured walls intermediate the ends thereof, conveyers between said walls, and means for conducting a heating medium to said chamber.

36. In an apparatus of the character described, a breaker-chamber, a breaker therein comprising a supporting-shaft, a plurality of breaker-arms fixed upon said shaft, conveyer-blades also fixed to said shaft, a plurality of loosely-mounted breaker-arms, and a conveyer-chamber, a conveyer-shaft projected longitudinally thereof, apertured walls intermediate the ends of said shaft, conveyers between said walls, means for conducting a heating medium to said walls, and independent heat-conducting means leading to said chamber.

37. In an apparatus of the character described, a breaker-chamber, a breaker therein comprising a supporting-shaft, a plurality of breaker-arms fixed upon said shaft, conveyer-blades also fixed to said shaft, a plurality of loosely-mounted breaker-arms, and a chamber, a plurality of apertured hollow walls extending transversely thereof, means for conducting heat to the interior of said walls, a conveyer, an exhaust, and independent means for conducting heat to said chamber.

38. In an apparatus of the character described, a breaker-chamber, a breaker therein comprising a supporting-shaft, a plurality of breaker-arms fixed upon said shaft, conveyer-blades also fixed to said shaft, a plurality of loosely-mounted breaker-arms, and a chamber, a plurality of apertured hollow walls extending transversely thereof, braces for said walls, means for conducting heat to the interior of said walls, a conveyer, an exhaust, and independent means for conducting heat to said chamber.

39. In an apparatus of the character described, a breaker-chamber, a breaker therein comprising a supporting-shaft, a plurality of breaker-arms fixed upon said shaft, conveyer-blades also fixed to said shaft, a plurality of loosely-mounted breaker-arms, and a conveyer-chamber, a plurality of apertured hollow walls extending transversely thereof, a conveyer, a heater, conduits from said heater to the interior of said walls and to the interior of said chamber, a pug-mill and a blast-conduit leading from the discharge thereof.

40. In an apparatus of the character described, a breaker-chamber, a breaker therein comprising a supporting-shaft, a plurality of breaker-arms fixed upon said shaft, conveyer-

blades also fixed to said shaft, a plurality of loosely-mounted breaker-arms, and a conveyer-chamber, a plurality of apertured walls extending transversely thereof, a conveyer, a heater, a plurality of blast-conduits leading from said heater to said chamber, and exhausts leading from said chamber.

41. In an apparatus of the character described, a breaker-chamber, a breaker therein comprising a supporting-shaft, a plurality of breaker-arms fixed upon said shaft, conveyer-blades also fixed to said shaft, a plurality of loosely-mounted breaker-arms, and a conveyer-chamber, a plurality of apertured hollow walls extending transversely thereof, a conveyer, a heater, a plurality of blast-conduits leading from said heater to the said walls and to said chamber, and exhausts leading from said chamber.

42. In an apparatus of the character described, a breaker-chamber, a breaker therein comprising a supporting-shaft, a plurality of breaker-arms fixed upon said shaft, conveyer-blades also fixed to said shaft, a plurality of loosely-mounted breaker-arms, and a conveyer-chamber, a plurality of apertured walls extending transversely thereof, a conveyer, a heater, a plurality of blast-conduits leading therefrom to opposite end portions of said chamber, a vapor-conduit leading from said heater to said chamber, and exhausts from said chamber.

43. In an apparatus of the character described, a breaker-chamber, a breaker therein comprising a supporting-shaft, a plurality of breaker-arms fixed upon said shaft, conveyer-blades also fixed to said shaft, a plurality of loosely-mounted breaker-arms, and a conveyer-chamber, a plurality of apertured walls extending transversely thereof, a conveyer, a heater, a plurality of blast-conduits leading therefrom to opposite end portions of said chamber, a vapor-conduit leading from said heater to said chamber, and exhausts from said chamber intermediate said vapor-conduit and said blast-conduits.

44. In an apparatus of the character described, a breaker-chamber, a breaker therein comprising a supporting-shaft, a plurality of breaker-arms fixed upon said shaft, conveyer-blades also fixed to said shaft, a plurality of loosely-mounted breaker-arms, and a conveyer-chamber, conveyers therein, apertured walls between said conveyers, a heater, a blast-conduit leading through the heater to said conveyer-chamber, and an exhaust from said chamber, in combination with a steam-supply conduit leading through said heater and to the said walls.

45. In an apparatus of the character described, a breaker-chamber, a breaker therein comprising a supporting-shaft, a plurality of breaker-arms fixed upon said shaft, conveyer-blades also fixed to said shaft, a plurality of loosely-mounted breaker-arms, and a con-

veyer-chamber, a conveyer-shaft, conveyers thereon, apertured walls between said conveyers, a heater, and conduits therefrom to said conveyer-chamber, in combination with 5 a steam-supply conduit leading through said heater and to the said walls.

46. In an apparatus of the character described, a breaker-chamber, a breaker therein comprising a supporting-shaft, a plurality of 10 breaker-arms fixed upon said shaft, conveyer-blades also fixed to said shaft, a plurality of loosely-mounted breaker-arms, and a conveyer-chamber, a conveyer-shaft projected longitudinally thereof, apertured walls intermediate the ends thereof, conveyers between 15 said walls, and means for conducting a heating medium to said chamber, in combination with a steam-supply conduit leading through said heater and to the said walls.

20 47. In an apparatus of the character described, a breaker-chamber, a breaker therein comprising a supporting-shaft, a plurality of breaker-arms fixed upon said shaft, conveyer-blades also fixed to said shaft, a plurality of 25 loosely-mounted breaker-arms, and a conveyer-chamber, a conveyer-shaft projected longitudinally thereof, apertured walls intermediate the ends of said shaft, conveyers between 30 said walls, means for conducting a heating medium to said walls, and independent heat-conducting means leading to said chamber, in combination with a steam-supply conduit leading through said heater and to the said walls.

35 48. In an apparatus of the character described, a breaker-chamber, a breaker therein comprising a supporting-shaft, a plurality of breaker-arms fixed upon said shaft, conveyer-blades also fixed to said shaft, a plurality of 40 loosely-mounted breaker-arms, and a conveyer-chamber, a plurality of apertured walls extending transversely thereof, a conveyer, a

heater, a plurality of blast-conduits leading from said heater to said chamber, and exhausts leading from said chamber, in combination 45 with a steam-supply conduit leading through said heater and to the said walls.

49. In an apparatus of the character described, a breaker-chamber, a breaker therein comprising a supporting-shaft, a plurality of 50 breaker-arms fixed upon said shaft, conveyer-blades also fixed to said shaft, a plurality of loosely-mounted breaker-arms, and a conveyer-chamber, a plurality of apertured hollow walls extending transversely thereof, a 55 conveyer, a heater, a plurality of blast-conduits leading from said heater to the said walls and to said chamber, and exhausts leading from said chamber, in combination with a steam-supply conduit leading through said 60 heater and to the said walls.

50. In an apparatus of the character described, a breaker-chamber, a breaker therein comprising a supporting-shaft, a plurality of 65 breaker-arms fixed upon said shaft, conveyer-blades also fixed to said shaft, a plurality of loosely-mounted breaker-arms, and a conveyer-chamber, a plurality of apertured walls extending transversely thereof, a conveyer, a heater, a plurality of blast-conduits leading 70 therefrom to opposite end portions of said chamber, a vapor-conduit leading from said heater to said chamber, and exhausts from said chamber, in combination with a steam-supply conduit leading through said heater and 75 to the said walls.

In witness whereof we have hereunto set our hands in the presence of two witnesses.

PATRICK REYNOLDS.

JOSEPH ALPHONSE RAOUl BEDARD.

Witnesses:

F. H. GIBBS,
T. MYNARD.
